(57) **CLAIM**

I claim the ornamental design for an inscribed bullion article, as shown and described.

DESCRIPTION

FIG. 1 is a perspective view of an inscribed bullion article showing my new design;

FIG. 2 is a plan view of the bullion article as generally illustrated in FIG. 1;

FIG. 3 is a first end view of the bullion article as shown in FIG. 2, a corresponding second end view being a mirror image thereof;

FIG. 4 is a plan view of the bullion article and illustrating a second face thereof; and,

FIG. 5 is a first side view of the bullion article as shown in FIG. 4, a corresponding second side view being a mirror image thereof.

It being understood that the broken lines are for illustrative purposes only.
